UNITED STATES PATENT OFFICE.

ALFRED H. HUMPHREY, OF SALEM, NEW YORK.

SIGN.

Application filed May 5, 1926. Serial No. 106,904.

My invention relates to a sign adapted for use in various situations such as at stores and on buildings, generally, for example, and the invention relates particularly to a sign, usually vertically disposed and adapted to be illuminated at opposite sides.

The general object of my invention is to provide a structure embodying separate units, each unit including a casing and individual illuminating means therefor.

Objects also of my invention are to provide a sign in which a large number of similar units may be incorporated to facilitate and economize in the manufacture and assembly; to provide an arrangement of the units in a manner to form space for the conductor wires of electric lamps as well as to afford space for convenience in maintenance of the sign and for incorporating and renewing the lamps or repairing the conductor wires; to provide a form and arrangement of units making for compactness in the structure; to provide a structure in which the units are supported by a framework permitting either face of the sign having the letters or symbols to be removed whenever desired, leaving the assembled units intact; and to provide the framework with a convenient arrangement of ladder members.

The manner and means whereby the above and other objects are attained will clearly appear as the description proceeds.

Reference is to be had to the accompanying drawings forming a part of this specification, it being understood that the drawings are merely illustrative of one example of the invention.

Figure 1 is a side elevation of a sign embodying my invention;

Figure 2 is a vertical section in a plane indicated by the line 2—2, Figure 1;

Figure 3 is a rear view of the sign with supporting bracket arms in vertical section as indicated by the line 3—3, Figure 1;

Figure 4 is a horizontal section on the line 4—4, Figure 1;

Figure 5 is a horizontal section on the line 5—5, Figure 1;

Figure 6 is a detail in vertical section showing parts of the casings of two adjacent units and the intermediate framework;

Figure 7 is an enlarged view in horizontal section through one of the central letters of a unit as indicated by the line 7—7,

Figure 8 is a perspective view of one of the letters, the view being given to illustrate the perforations at the sides of a letter as well as at the face thereof;

Figure 9 is an elevation, with parts 60 broken out, of the diffusing means;

Figure 10 is a horizontal section through one of the letters illustrating the employment of one arrangement for producing varied color effects in the letters;

Figure 11 is a view similar to Figure 10 but showing an alternative method of producing color effects.

In carrying out my invention in accordance with the illustrated example, a framework is provided including front bars 15 extending from side to side and rear bars 16. The rear bars are mounted in the form shown on bracket arms 17 adapted to be secured to a building front, for example, or other support conventionally indicated at A.

The front 18 of the sign is disposed in front of the frame bars 15 concealing the same. The rear bars 16 are exposed and may be utilized as a ladder for climbing 80 vertically along the back of the sign for renewing the lamps hereinafter referred to or making repairs or the like.

The sides of the frame are illuminated and provided with the legends, the sign shown having at one side the letters making up the word "Stationery". The letters or symbols at the opposite side of the sign from the word "Stationery" may be of any desired character. Each side has a face plate 19 on which is formed raised letters 20 perforated at the face of the letter and at the top, bottom and sides as will clearly appear from Figures 1, 7 and 8.

Where color effects are desired, a sheet 21 of transpicuous colored material such as translucent or transparent celluloid may be employed.

In the form shown in Figure 10 the raised letters 120 on the face plate 119 are perforated as are the letters 20 and for color effects a zig-zag sheet 121 extending across the letter between the planes of the back and front of the letter. Alternate bends in the zig-zag sheet 121 may be colored differently 105 from the remaining bends so that as the letter is looked at from one side it gives a different color effect from the same letter looked at from the opposite side.

In Figure 11 the face plate 219 has letters 110

220 the same as letters 20 and 120 and for color effects, parallel color strips 221 are employed having one or more colors.

The frame supports two vertical series of 5 illuminating units 22. It will be seen best in Figure 2 that each unit consists of a casing disposed vertically and flaring toward the top and bottom. The series of units 22, it will be seen, are in staggered relation to 10 each other, the back of one casing being disposed so as to overlap the two casings in the adjacent vertical series. Each casing has illuminating means which in practice consists of an electric lamp 23. The several 15 backs of the units 22 are spaced from each other and thereby form a zig-zag duct or space 24 accommodating electric conductors 25 and affording clearance for installation and repairs. One series of units 22 is completed by the top and bottom units 122 thereof being made smaller than the main series of units 22. The numeral 27 indicates lamp sockets.

In Figure 3 it will be seen that each unit 25 22 and 122 has a door 28 affording access to the lamps for placing and renewing the same.

The single lamp 23 centrally located serves to illuminate the flaring casings of each unit 22 or 122. In order that a given 30 centrally located lamp in a particular unit 22 or 122 may not glare when viewed through a letter directly in front of the lamp, I provide a diffusing medium, designated generally by the numeral 29. Each 35 diffusing unit 29 comprises a frame 130 usually of back and front wire mesh coverings 30 and an intermediate sheet 31 of transpicious material such as a sheet of woven fabric, paper, or celluloid, preferably woven fabric. The diffusing medium thus 40 constructed embodies strength and is effective for the purpose of diffusion. A diffusing medium 29 is employed extending over whatever area may be necessary to effect 45 two purposes, that is to say, to prevent the light being directly viewed with the incident glare through the perforations of a given letter, and secondly, by diffusing the light directly in front of the lamp and therefore 50 where the light is strongest the illumination is equalized at a letter directly in front of the lamp or close to the location of the lamp and the letters more remote from the lamp.

The casings of the units 22 and 122 are of 55 such a character as to provide a reflecting surface at the front. In practice, enameled sheet metal serves the purpose. The preferred mode of connecting the reflector casings 22 and 122 of each illuminating unit 60 is held to the bars 15 and 16, as follows: To each bar 15 and 16, an angle iron 32 is secured with one flange of the angle iron deflected laterally outward. On the reflector casing of each unit is similarly secured a 65 vertical angle iron 33. Thus, the angle irons

33 are disposed directly inside of the angle irons 32 and the laterally deflected flanges of the adjacent angle irons 32, 33 lie in close relation as clearly seen in Figure 5. The face plate 19 has rigid therewith a U-shaped 70 edge member 34 at each side edge to embrace the laterally directed flanges of the respective angle irons 32, 33. The arrangement is such that the face plate 19 carrying the letters 20 and having the edge members 75 34 may be slid vertically to permit of a particular legend being incorporated in the sign or to afford access to the interior of the respective series of units.

The diffusion units 29 are secured to the 80 backs of the face plates 19 by any suitable means such, for example, as soldering.

Referring particularly to Figure 6, it will be observed that the adjacent ends of units 22 of any vertical series are united to assist 85 in producing rigidity in the structure and to coordinate the successive vertically disposed units in the series. For the purpose, use is made in the illustrated example of angle irons 35 at the edge of each flaring 90 unit 22. Flanges of said angle irons 35 are disposed vertically toward each other and adjacent the plane of a face plate 19. The vertically disposed flanges of said angle irons 35 are secured to the adjacent bars 15, 95 16, respectively, of the framework and materially contribute to the completion of the framework and the strengthening thereof. In practice spot-welding is usually utilized as the means to secure the angle irons 35 100 to the frame bars 15, 16.

It is explained that with the letters or other characters employed, raised and perforated as described, the illumination of the letters is greatly promoted and the visibility 105 very markedly increased.

I would state furthermore that while the illustrated example constitutes a practical embodiment of my invention, I do not limit myself strictly to the exact details herein 110 illustrated, since, manifestly, the same can be considerably varied without departure from the spirit of the invention as defined in the appended claims.

Having thus described my invention, I 115 claim:

1. A sign including two series of casings flaring outwardly and an electric lamp in each casing, the two series of casings being disposed back to back and in staggered relation and spaced to form a sinuous duct therebetween, and conductor wires disposed in said duct and connected with said lamp.

2. A sign of the class described including a framework having transverse bars at the 125 back and front, face plates at the sides, flaring units each having at the front thereof a plurality of symbols, and means securing said units to said cross bars of the framework.

3. A sign including a frame having transverse bars at the back and front, face plates at the sides of the sign bearing symbols, a series of illuminating units for said face plates, and means slidably connecting said units with said face plates.

4. A sign including a frame, a series of flaring units connected with said frame, lamps to illuminate said units, a front adapted to be illuminated by said lamps and bearing symbols adapted to emit light, and a diffusing medium in front of each lamp, each diffusing medium comprising back and

front layers of wire mesh and an intermediate sheet of diffusing material. 15

5. A sign including a frame, face plates at the sides of the frame and bearing symbols, series of illuminating units for said face plates, means connecting the several units with said frame, members on said face plates at the side edges, and members respectively on the frame and on the units engageable by said edge members of the face plates. 20

ALFRED H. HUMPHREY.
